J. Plegar,
Lock Hinge.

No 13,321.

Patented July 24, 1855.

UNITED STATES PATENT OFFICE.

JOSEPH PLEGAR, OF BIRMINGHAM, PENNSYLVANIA.

HINGE.

Specification of Letters Patent No. 13,321, dated July 24, 1855.

To all whom it may concern:

Be it known that I, JOSEPH PLEGAR, of Birmingham, in the county of Allegheny and State of Pennsylvania, have invented a new and useful Improvement upon Hinges; and I do hereby declare that the following is a full and exact description.

Letter *a* represents a full view of the hinge open.

10   *b* is the bolt on the pin part of the hinge.
c is an end view of the bolt showing the pivot on the top of it.

d is a lug to avoid the falling of the shutter when closed.

15   *e* is the cup or socket.
f is an end view of the socket showing the bearings.

The nature of my invention consists in making the upper end of the pin bolt shaped 20 over which the cup or socket of the upper part of the hinge falls, the cup or socket having a square recess for the bolt, and forming a pivot upon which it revolves when freed from the cup or socket. The 25 internal arrangement of the upper part of the hinge embraces three distinct features: 1st, its cup or socket for the reception of the bolt; 2nd, its bearings for the pivot of the

bolt, in this position the bolt being completely protected from accident or weather. 30

The advantages of my arrangement are, 1st, the positive accuracy of this hinge through the chilling process, the cup or socket being made of uniform size and shape by the metal running around chills that are 35 turned to gage; 2nd, the durability of this arrangement; the inclosure or cup or socket becomes hardened by the chilling process; also there is a smooth surface produced by which the free action of the hinge is augmented; also its security by its inclosed position from rust or the liability to accident; 40 3d, the certainty of fastening shutters open, as the cup falls over the pin, which enters the socket and thereby dispenses with other 45 fastenings on the wall which are always uncertain.

What I claim as my invention and desire to secure by Letters Patent is—

Making a bolt on the pin part of the hinge 50 and a cup or socket in the upper section of the hinge to receive the bolt, as herein set forth.

Witnesses: JOSEPH PLEGAR.

ANDREW LONG,
A. MEADER.
